[57] CLAIM

The ornamental design for a hand-held vacuum cleaner appliance, substantially as shown and described.

DESCRIPTION

FIG. 1 is a perspective view of a hand-held vacuum cleaner appliance showing my new design;
 FIG. 2 is a right side elevational view, the left side being a mirror image thereof;
 FIG. 3 is a bottom plan view thereof;
 FIG. 4 is a top plan view thereof;
 FIG. 5 is a front elevational view thereof;
 FIG. 6 is a rear elevational view thereof.
 The electrical cord has been shown fragmentarily in FIGS. 1-3 and 6 for convenience of illustration.
